FLOODLIGHT

Fred M. Gore, Dallas, Tex., assignor to
Esquire, Inc., New York, N.Y.

Filed Apr. 11, 1973, Ser. No. 350,171

Term of patent 14 years

Int. Cl. D26—03, 05

U.S. Cl. D48—20 K

FIG. 1 is a top view of a floodlight embodying my design;

FIG. 2 is a view of one side of the floodlight;

FIG. 3 is a front view of the floodlight;

FIG. 4 is a view of the other side of the floodlight;

FIG. 5 is a bottom view of the floodlight; and

FIG. 6 is a rear view of the floodlight.

The flat surface on the front of the floodlight is a window.

I claim:

The ornamental design for a floodlight, substantially as shown and described.
